UNITED STATES PATENT OFFICE

2,379,761

ELECTRIC SWITCH

Harold E. Strang, Ardmore, Pa., assignor to General Electric Company, a corporation of New York

Application July 9, 1943, Serial No. 493,979

8 Claims. (Cl. 200—48)

My invention relates to improvements in electric switches and more particularly to improvements in disconnecting switches, and especially disconnecting switches of the angularly movable blade type.

In the application of disconnecting switches, it is necessary to increase the separation distance with increase in the voltage of the circuit. Consequently, high operating voltages require a relatively long movable switch conducting member, usually in the form of an angularly movable blade. Inasmuch as a relatively strong contact pressure is desired between the blade and stationary contact, a considerable force is required to release the blade member from the stationary contact member by the operating means which effects the angular movement of the blade member. This of itself involves a matter of stress distribution such that parts like ceramic insulators, for example, will not be overstressed or subjected to stresses which they are not adapted to sustain. But when disconnecting switches are mounted outdoors, as is usual with high operating voltages, the blade member and its cooperating contact may become so coated with ice and the like adjacent their engaging parts that the difficulty of separating the blade member from its cooperating contact is greatly increased. Also, when the switch is open, ice may collect on the cooperating contact in such a way as to prevent switch closing engagement by the blade. To take care of all these conditions merely by strength of parts in the design of the switch would require such a massive construction as to render the design economically unfeasible.

An object of my invention is to provide means operable independently of the movement of the movable contact of an electric switch for breaking away ice formations and the like adjacent the engaging portions of the movable and stationary contacts when the switch is closed and from the stationary contact when the switch is open. Another object of my invention is to provide for an electric switch an ice breaking means by which an initial opening impulse is given to the movable contact after first breaking away ice formations from both contacts when they are engaged. A further object of my invention is to provide an improved electric switch wherein the ice clearing action and the initial operating impulse are accomplished by fluid pressure or other power operated means. These and other objects of my invention will appear in more detail hereinafter.

In accordance with my invention, I provide for an electric switch an ice breaking member which is movably positioned adjacent the stationary contact of the switch and is arranged to be actuated relatively to the stationary contact so as to break away ice formations thereon and also on the movable contact when in engagement with the stationary contact. Also in accordance with my invention, the ice breaking member is arranged upon further movement in the ice breaking direction to give an initial opening impulse to the movable contact when the switch is closed. Further in accordance with the preferred embodiment of my invention, I provide fluid pressure operated means for effecting the ice breaking movement of the ice breaking member and means in which energy is stored during such movement for effecting the return movement of the member.

My invention will be better understood from the following description when considered in connection with the accompanying sheet of drawings, and its scope will be pointed out in the appended claims.

In the accompanying drawing, Fig. 1 is a side elevation illustrating a circuit breaker and a disconnecting switch provided with ice breaking means embodying my invention; Fig. 2 is a side elevation on the line 2—2 of Fig. 1 to a larger scale, with parts broken away, illustrating the embodiment of my invention applied to the disconnecting switch in Fig. 1 with the switch closed and the ice breaking means in position to start the ice breaking action; Fig. 3 is a view similar to Fig. 2 showing the ice breaking movement completed and the disconnecting switch partly open; Fig. 4 is a sectional elevation on the line 4—4 of Fig. 2; and Fig. 5 is an exploded perspective of the disconnecting switch stationary contact and the ice breaking member.

For the purpose of illustrating an application of my invention, I have shown in Fig. 1 a single-pole unit of a double break, high voltage, gas blast circuit breaker and disconnecting switch combination, such as is disclosed, for example, in United States Letters Patent 2,306,186, issued December 22, 1942, but it is distinctly to be understood that my invention is not limited to this particular combination or the particular type of disconnecting switch illustrated. As shown, the switch combination comprises two similar circuit breaker interrupting means mounted within and on high voltage insulating shells 1 and 2, respectively, supported on suitable insulating columns 3 and 4 which are mounted on a supporting frame 5 of suitable structural form. Each interrupting unit is provided with upper and

lower terminals 6 and 7, respectively, and a muffler type exhaust opening 8. Also supported on the frame 5 is a gas tank 9 which is adapted to supply both interrupting units through conduits 10. The lower terminals of the interrupting units are provided with suitable contact means 11, illustrated as of the jaw type, for coacting with a movable disconnecting switch contact 12 of the blade type. As shown, this contact 12 is mounted for movement relatively to the terminals 7 on an insulating support 13 which is rotatably mounted on the frame 5. The disconnecting switch contact 12 when rotated counterclockwise, as viewed looking down on the switch, through a predetermined angle disconnects each interrupting unit at its terminal 7 to disconnect the power circuit. Any suitable means may be provided for actuating the blade 12, but, as illustrated, the insulating support 13 is suitably journaled on the frame for rotative movement in response to the actuation of suitable operating means mounted in a housing 14 and illustrated in part by bevel gearing 15. This operating means, of itself, constitutes no part of my present invention.

In accordance with my invention, I provide means for removing ice formations and the like from the cooperating contacts 11 and 12 of the disconnecting switch adjacent their engaging portions. For this purpose, I provide a member 16 which is movably mounted adjacent one of the cooperating contacts 11 and provided with means, such as wedge-shaped bifurcations 17, for breaking ice away from both contacts when the disconnecting switch is closed and from the stationary contact when the disconnecting switch is open. In order to obtain maximum conductivity and also to provide the maximum of distributed shearing action on ice formations adjacent the stationary contact 11, this jaw contact may take the form of a plurality of spaced pairs of resilient contact fingers 18 and 19 in the spaces between which the bifurcations 17 of the ice breaking member 16 are slidable. The space between opposed bifurcations 17 is somewhat greater than the thickness of the blade contact 12 so as to slide across this contact and shear ice therefrom when the disconnecting switch is closed.

Further in accordance with my invention, I make the member 16 reciprocably movable and provide means for forcibly driving it in the ice removing direction and also means for returning the member 16 to its initial position shown in Figs. 2 and 4. As shown, the actuating means is of the fluid pressure operated type, and more specifically, it may be of the pneumatic type and arranged for operation from the gas supply tank 9. As illustrated, the actuating means comprises a cylinder 20 which is suitably conductively secured to the circuit breaker terminal 1. Within the cylinder 20, there is slidably mounted a piston 21 suitably secured to the end of a piston rod 22 on the ice breaking member 16. For actuating the member 16 in the ice breaking direction, suitable conduit means 23 extend from the supply tank 9 by way of the conduit 24 and through a two-way valve 25 which may be actuated by suitable means indicated as an operating rod 26. The conduit 23 is suitably connected to the terminal 1, which is provided with a port 27 registering with a port 28 in the cylinder 20 so as to admit air back of the piston 21 and thereby force the member 16 outwardly between the contact fingers 18 and 19 and across the end of the blade 12 when it is in the switch closed position.

Further in accordance with my invention, I provide means for returning the ice breaking member 16 to the initial position. As shown, this return movement means is of the type in which energy is stored during the ice breaking movement of the member under the action of the gas pressure from the tank 9. For this purpose, this return movement means may be a helical spring 29 positioned on the rod 22 between the cylinder head 30 and the piston 21. For relieving the back pressure in the cylinder on the ice breaking movement of the piston 21, this cylinder head may be provided with a suitable exhaust port 31. When the two-way valve operating rod 26 is pulled down a predetermined amount, air is admitted from the gas supply tank through the pipe 24 to the conduits 23 whereby to force the ice breaking member 16 at each jaw contact 11 in the ice breaking direction. Upon moving the rod 26 up to the exhaust position shown in Fig. 1, the gas supply is shut off and the conduits 23 are open to the air for exhaustion of the gas in the cylinder 20 so that the spring 29 may return the ice breaking member to its initial position.

Also in accordance with my invention, I may so arrange the ice breaking member 16 that it provides an initial opening impulse to the blade 12 in order forcibly to move the blade relatively to the contacts 11 whereby to relieve any sticking tendency that the contacts 11 and 12 may have as a result of corrosion or freezing action which has not been entirely released by the prying and shearing action of the wedge-shaped elements 17. For this purpose, the body 16 of the ice breaking member may be made of such width as to engage the inner edge of the blade following the major ice breaking action and push the blade relatively to the contacts 11 so as forcibly to produce movement of the blade relatively to the contacts 11.

Assuming the parts positioned as shown in Figs. 1, 2 and 4, and that it is desired to open the disconnecting switch while there is ice formation in and around the engaging parts of the contacts 11 and 12, the valve operating rod 26 is pulled down sufficiently to admit gas from the supply tank 9 through the conduit 24 to the conduits 23 and thence back of the piston 21 at each jaw contact 11 whereby forcibly to actuate the ice breaking mechanism 16 in the ice breaking direction. Under these conditions, the wedge-shaped bifurcations 17 on the member 16 shear and crack the ice away from the contacts 11 and 12, and subsequently the body portion of the member 16 at each jaw contact engages the adjacent end of the blade 12 to move it forcibly relatively to the contacts 11. During this movement, energy is stored in the return springs 29. When the ice has been suitably cleared from the contacts and the blade given its initial impulse, the valve actuating rod 26 may be raised upwardly to the position shown in Fig. 1 to permit exhaustion of the air from the cylinders 20 and to allow the springs 29 to return the ice breaking members 16 to their initial positions. The disconnecting switch operating means may then be actuated to open the switch. If the switch is open and ice has formed in and around the stationary contacts 11 and the fingers thereof, then prior to closure of the switch, the ice breaking members 16 may be actuated as heretofore described so as to clear the ice away from the stationary contacts. Under extreme conditions, it is possible to leave the members 16 in the full

out position shown in Fig. 3 so that as the blade 12 is operated toward the closed position, any ice accumulated on the blade ends may be sheared therefrom by the wedge-shaped elements 17. In this case, the members 16 must be allowed to return to the initial position by suitably opening the valve 25 to exhaust the air behind the pistons 21 before completing the final closing movement of the blade 12.

While I have shown and described my invention in considerable detail, I do not desire to be limited to the exact arrangement shown, but seek to cover in the appended claims all those modifications that fall within the true spirit and scope of my invention.

What I claim as new and desire to secure by Letters Patent of the United States is:

1. An electric switch comprising relatively movable, cooperating contacts and means for removing ice and the like from said contacts adjacent their engaging portions comprising a member movably mounted adjacent one of said contacts and provided with means movable across said contacts when in the switch closed position and prior to relative movement thereof from said position for breaking ice away from said contacts upon movement of the member, and means for effecting the ice breaking movement of said member.

2. An electric switch comprising a movably mounted contact and a cooperating stationary contact and means for removing ice and the like from said contacts adjacent their engaging portions comprising a member provided with ice breaking elements and mounted adjacent said stationary contact for movement relatively thereto with said elements movable across said movable contact when in the switch closed position, and means for effecting the ice breaking movement of said member.

3. An electric switch comprising a movably mounted blade contact, a cooperating stationary jaw contact having a plurality of spaced pairs of opposed contact fingers, and means for breaking ice and the like away from said fingers comprising a member provided with a plurality of spaced wedge-shaped portions and mounted for movement adjacent said jaw contact with said portions slidable in the spaces between the contact fingers on each side of the jaw contact and across said blade contact when in the switch closed position, and means for effecting the movement of said member.

4. An electric switch comprising a rotatably mounted blade contact, a cooperating stationary jaw contact having a plurality of spaced pairs of opposed contact fingers, and means for removing ice and the like from said contacts adjacent their contacting portions comprising a member movably mounted adjacent said jaw contact and

provided with wedge-shaped bifurcations movable in the spaces between the contact fingers on each side of the jaw contact and across the blade contact when in the switch closed position, and pneumatic means for effecting the movement of said member.

5. An electric switch comprising relatively movable cooperating contacts and means for removing ice and the like from said contacts adjacent their engaging portions comprising a reciprocably movable member mounted adjacent one of said contacts and provided with means for breaking ice away from the contacts upon movement of the member in one direction and for subsequently engaging the other of said contacts to give an initial opening impulse thereto, pneumatic means for effecting movement of said member in said one direction, and means in which energy is stored during said movement for effecting movement of said member in the opposite direction.

10 6. An electric switch comprising relatively movable cooperating contacts and means for removing ice and the like from said contacts adjacent their engaging portions comprising a reciprocably movable member mounted adjacent one of said contacts and provided with means for breaking ice away from the contacts upon movement of the member in one direction and for subsequently engaging the other of said contacts to give an initial opening impulse thereto, and means for effecting movement of said member in said one direction.

15 7. An electric switch comprising a movably mounted blade contact, a stationary jaw contact having a plurality of spaced pairs of opposed contact elements positioned for engagement by one end of said blade contact, and means for breaking ice and the like away from said contact elements comprising a reciprocably movable member mounted adjacent said jaw contact and provided with portions slidable in the spaces between the contact elements on each side of the jaw contact and across said blade contact when in the switch closed position upon movement of the member in one direction, pneumatic means for effecting movement of said member in said one direction, and resilient means in which energy is stored during said movement for effecting movement of said member in the opposite direction.

20 8. An electric switch comprising a movable contact, a cooperating stationary jaw contact, and means for removing ice and the like from the jaws of said jaw contact comprising a wedge-shaped member movably mounted adjacent the jaws of said jaw contact and movable across the movable contact when in the switch closed position, and means for effecting the movement of said member.

HAROLD E. STRANG.
